UNITED STATES PATENT OFFICE.

FRANZ LÖSEL, OF BRUNN, CZECHOSLOVAKIA.

ELASTIC-FLUID TURBINE.

Application filed March 25, 1926. Serial No. 97,179.

This invention relates to elastic fluid turbines particularly turbines for utilizing high pressure and high temperature fluids.

- The objects of the invention are to improve the turbine construction; to render same more capable for reliable and safe use of high temperatures and pressures; to increase the turbine reliability, security and safety; to provide means to take care of heat expansions during operation and for allowing stationary parts to expand freely without causing undue heat expansions, stresses and strains and without causing leakage losses due thereto; to hold stationary parts in operative position and their joints together fluid-tight; and to relieve stationary inner turbine parts from undesirable effects due to actions during operation.
- Other objects are to obtain relatively small temperature differences between inside and outside walls of certain carriers or supporting parts in turbines and to reduce also the pressure differences between inner and outer walls of these supporting parts to a relatively small amount and thus prevent unfavorable and undesirable movements during operation due to such differences.
- This is accomplished according to the present invention by separate enclosing and cooperating means located one within another for carrying and supporting stationary guide means of the turbine such as diaphragms and nozzles within the casing and jacketing these carrying means in a novel combined manner by high pressure high temperature fluids. The fluids used for jacketing and heating counteract the radial heat expansions of the internal stationary parts but without hindering the heat expansions of same and counteract or tend to counteract the internal pressures within the separate carriers and tend to keep the joints selftightening and fluid-tight; the different carrying means being preferably jacketed, surrounded and heated from separate enclosing outer and inner heating and pressure fluid chambers forming different enclosing outer and inner jacketing zones or chambers for the carriers which are therefore heated and easily penetrated by heat, the heat expansions of the different parts, therefore, taking place in an improved manner. The outside walls of the carrying

means are subjected to somewhat higher temperatures than their inside walls, and the outer carrying parts are subjected to higher temperatures and to initial, larger and quicker expansions than the inner parts. The inner parts are, therefore, able to expand freely into the outer parts so that all of these parts follow the movements due to heat and do not interfere therewith and the outer counteracting forces keep or tend to keep certain of their joints fluid-tight, thereby preventing opening and leaking at same.

Other objects and advantages will appear hereinafter.

The invention consists in general in the provision of separate and independent rotor enclosing carrier bodies for supporting and carrying stationary guide means such as the diaphragms and nozzles preferably in separate groups within the turbine and in surrounding and heating the same by fluid jackets filled with elastic fluid under pressure and in the provision of separate supporting or carrying means for the separate rotor enclosing carrier bodies, such carrier means being preferably located outside of the carrier bodies and formed by an inner casing portion which encloses the separate carrier bodies and the high temperature high pressure fluid jackets therearound and forms with another outer casing portion an outer heating jacket or chamber filled with higher temperature fluid under pressure which surrounds the inner jackets and inner separate rotor enclosing carrier bodies and the guide means therein.

In the drawings:

Fig. 1 shows a longitudinal section through and a side view of a multistage disc wheel turbine embodying an example of the invention;

Fig. 2 is a cross section through section line $\alpha-\alpha$ of Fig. 1;

Fig. 3 shows a longitudinal section through the upper half of a disc wheel turbine embodying a modification; and

Fig. 4 is a similar section showing a further modification of the invention.

Referring to the drawings Figs. 1 and 2: 1 is the turbine shaft, 2 the rotor wheels or rotor discs shown integral with the shaft, 3 are the diaphragms or partitions located between the rotor wheels, 4 are guide nozzles, guide blades or guide canals provided on the diaphragms, and 5 are the rotating blade

canals, rotating blades or moving buckets provided on the rotor wheels. The diaphragms 3 and guide nozzles 4 are carried and supported by the rotor enclosing separate carrier bodies 6 and two such carrier bodies are shown within the turbine (Fig. 1). Each carrier body 6 carries a part or group of the guide nozzles and partitions and forms with the same separate groups of guide means independent of each other. Two such separate individual diaphragm groups may be provided, as shown in Fig. 1. The carrier bodies 6 form ring-cylindrical axially divided carrying means in which the guide means fit fluid-tight by means of abutting surfaces. The carrier bodies 6 are carried and supported by the inner casing portion 7 and suitably connected therewith, as for example shown in Fig. 1 by means of a groove 8 for each carrier body 6 and a projecting ring-cylindrical part 9 on the outer periphery of each carrier body 6. 10 is a radial clearance at the outer periphery between the ring-cylindrical part 9 of each carrier body and the bottom of the groove 8, but the side surfaces of the projection 9 fit tightly into the groove 8. To obtain a better fit, tightening means, for example tightening rings (not shown) of a suitable metal, may be provided in certain cases between the side surfaces of the projection 9 and groove 8.

The construction of the carrier bodies 6 and the casing part 7 is generally similar to that disclosed in my application Ser. No. 14,022, filed March 9, 1925 as a division of my application Ser. No. 657,375, filed August 14, 1923.

11 is a casing portion for the high pressure end of the turbine and 12 a casing portion for the lower pressure end, both being connected together in a suitable manner, for example as shown in Fig. 1 by means of the radial flanges 13. The inner casing portion 7 carrying and supporting the carrier bodies 6 is shown integral with the lower pressure end casing portion 12. The portion 7 is connected with portion 12 at the lower pressure end of the turbine and projects therefrom into the higher pressure end of the higher pressure casing part 11, but is spaced from the casing part 11 and forms therewith an outer heating and pressure chamber or jacket 14 and with the carrier bodies 6 an inner separate heating and pressure chamber or jacket 15. The outer chamber or fluid space 14 is filled with high pressure fluid through the clearance or opening 16 provided between the high pressure end of the first diaphragm group and the first rotor wheel enclosing casing or nozzle portion on the high pressure casing 11, and the inner chamber 15 is filled with high pressure fluid but of lower pressure than in the space 14 through the clearance or opening 17 between the carrier bodies 6. The fluid in the outer

jacket 14 surrounds also the high pressure end of the first diaphragm group within the inner casing portion 7.

18 is a high pressure fluid intake or admission pipe; 19 the high pressure fluid admission space or chamber leading to the first nozzles 20 for admission to the turbine. Preferably the turbine is constructed for full admission or admission of the elastic fluid to the canals around the whole periphery. 21 is the discharge chamber or outlet space and 22 a discharge or outlet pipe leading fluid from the turbine for further use. The turbine is shown as a high pressure back pressure turbine and the discharge pipe 22 80 may lead to a further turbine (not shown) for utilizing the back pressure fluid therein. 23 is the high pressure turbine gland; 24 the gland on the lower pressure side of the turbine, and 25 are the bearings for the rotor. 85 26 is a lagging and in certain cases insulating means (not shown) may also be provided. The guide nozzles 4 between the diaphragms 3 and carrier bodies 6 are shown as separate individual blade or nozzle elements 90 provided on the outer periphery of the diaphragms 3, the guide canals in these nozzle elements being preferably formed by machining or milling.

By the novel method and combined structure of carrying stationary guide means such as nozzles and diaphragms in separate individual groups by separate independent rotor enclosing carrier bodies and carrying and supporting these individual carrier bodies 100 and the guide means or groups of individual guide means therein by separate carrying and supporting means outside thereof but within the turbine casing and locating these different carriers one in another, forming 105 and connecting same so that they are free to expand due to heat, and further by the provision of inner and outer heating and pressure chambers enclosing the different individual carriers and forming on the outside 110 and inside of the outer carrier means fluid heating and pressure chambers, a very favorable turbine structure is obtained for reliable and safe use and utilization of high pressure and high temperature elastic fluid. 115 Thereby are also secured the advantages of an almost equal temperature and relatively small pressure difference between the inner and outer walls of the carrying means so that the relative movements or the displacing of parts, dangerous for the turbine, do not take place due to heat expansions or pressure influences.

The high pressure end casing 11 may be an axially undivided casing portion, in which is provided the high pressure gland portion 27 on the high pressure end thereof as shown in Figs. 1 and 2. The high pressure gland portion 27 forms an axially divided or split cylindrical part or gland member. The end 120

- casing portion 12 on the lower pressure end, the carrier portion 7 connected therewith, and the carrier bodies 6 and diaphragms 3 there-within are axially divided or split. The 5 casing portions 11 and 12 are provided with the radial flanges 13 forming an abutting radial joint 29 and both are connected by suitable connecting or fastening means, for instance connecting screws (not shown). 28
- 10 is a shoulder on the lower pressure casing portion 12 for the higher pressure casing portion 11. The high pressure casing portion 11 is preferably made of a material of relatively high tensile strength, for example 25 of wrought iron, steel or boiler plate etc. and may be made or assembled in certain cases of a plurality of parts as shown in Fig. 1. The axially divided low pressure casing is preferably made of a suitable cast metal, 20 for instance cast iron, cast steel etc.
- Figure 3 shows three separate individual diaphragm groups within an outer cylindrical carrier part 7 of the lower pressure end casing portion 12. One of the diaphragms 25 3' in each group forms the carrier body for the other guide means in the same group. Each of these combined diaphragm and carrier bodies 3' is provided with a projecting ring-cylindrical part 8' which fits into the 30 groove 9 of the carrying part 7, substantially as shown in Fig. 1. The diaphragms 3 in each group are connected with the corresponding carrier body 3' by suitable connecting or fastening means such as bolts or 35 screws 30.
- 15 and 15' are two separate heating and pressure spaces or chambers within the outer carrier cylinder 7, filled by fluid under different pressures through the clearances or 40 spaces 17, 17' between the diaphragm groups. The separate inner heating and pressure chambers 15, 15' are surrounded by the outer heating and pressure chamber 14 filled by fluid under higher pressure than exists 45 within the inner pressure chambers.
- The fastening or connecting means between the high pressure casing portion 11 and lower pressure casing portion 12 are formed by a screw connection provided on 50 the outer periphery of the flangelike portions 13'. 31 is the large female connecting screw around the flanges 13'. The connecting screw 31 and the flanges 13' are preferably provided with right hand and left hand 55 screw threads for connecting the abutting parts. Other coupling means may be used in certain cases. In the joint 29 between the abutting flanges 13' are provided tightening means 32.
- 60 In Fig. 4 the last diaphragm 3'' of each separate individual diaphragm group forms the carrier body for the other diaphragms 3 in the same group. The carrier diaphragm 3'' forms a ring-cylindrical rotor enclosing 65 portion 6' which projects from the last dia-
- phragm in each separate group towards the higher pressure end of the same group and encloses the other diaphragms 3 of the same group and carries and supports same. The projecting part 8' for carrying each dia- 70 phragm group is located on or near the rear or lower pressure end of each group, so that the heating and pressure chambers are located only or mostly on the higher pressure end of each group and filled with fluid from 75 the high pressure end thereof. The higher pressure diaphragm group within the carrier 7 is surrounded and heated only by the fluid in space 14 filled from the high pressure end of this group. 80
- The outer carrier 7 is subjected to the pressures and temperatures of the fluids in the chambers 15'', 15''' and 14 located on the inside and outside thereof respectively. 85
- The screw coupling 31' connecting the high pressure and low pressure casing portions has a shoulder 32 by which the lower pressure casing portion 12 is drawn or pressed against the high pressure casing portion 11. By provision of such coupling means with a shoulder in certain cases the screw thread on the lower pressure casing portion may be dispensed with if the screw thread connection on the high pressure casing portion 11 and the shoulder 32 suffice to obtain 90 a suitable connection. 95
- By the provision of a separate axially undivided high pressure end casing portion 11 and of a separate axially divided lower pressure end casing portion 12 and by connecting the radial abutting joint 29 or flanges 13 in a suitable manner a favorable high pressure and high temperature turbine construction is secured. 100
- The high pressure casing end portion 11 may be made preferably of a material of high tensile strength such as steel, wrought iron or any other rolled, forged or pressed material of suitable quality, such as boiler plate. The low pressure end casing portion 12 may be made of a suitable cast metal such as cast steel, cast iron, a cast-steel-cast-iron mixture etc. as stated above. Such casing portions may consist of a plurality of 105 portions riveted together or each may be forged or pressed from a single piece. Also the diaphragms and carrier bodies may be connected in any suitable manner. Although the diaphragms and nozzle canals may be cast or made in any other suitable way, preferably separate nozzles are milled or machined, and used for connecting the carriers and diaphragms. Each of the carrier bodies may be also made of a plurality of 110 parts suitably assembled. 115
- Having thus described my invention, what I claim and desire to protect by Letters Patent is:
1. In a high pressure elastic fluid turbine, the combination of an outer casing portion, 120

- an inner casing portion spaced from said outer casing portion so as to form a steam chamber therebetween, a separate carrier body therewithin carried and enclosed by said inner casing portion said carrier body forming with the inner casing a steam chamber and stationary diaphragms with nozzle canals carried and supported by said carrier body.
10. 2. In a high pressure elastic fluid turbine, the combination of an outer casing portion, an inner casing portion, a fluid chamber therebetween, separate carrier bodies carried and supported by said inner casing portion, a fluid chamber between said carrier bodies and inner casing portion, and guide means carried by said carrier bodies.
15. 3. In a high pressure elastic fluid turbine, the combination of an outer casing portion, an inner casing portion suitably connected at its lower pressure end with said outer casing portion but free at its higher pressure end, and providing a fluid chamber between the same and said outer casing portion, a separate carrier carried and supported by said inner casing portion and providing a fluid chamber or space between the same and said inner casing portion, and diaphragms provided with guide nozzles within said carrier.
20. 4. In a high pressure elastic fluid turbine, the combination of a casing portion for the high pressure end, a casing portion for the lower pressure end having a portion projecting therefrom into said high pressure casing portion towards the high pressure end thereof but spaced therefrom to form a high pressure steam chamber, separate carrying bodies carried and supported within the casing for the lower pressure end said separate carrying bodies forming annular steam chambers within the low pressure casing and around the carrier bodies, and diaphragms provided with guide nozzle canals carried and supported by said carrying bodies.
25. 5. In an elastic fluid turbine, the combination of a casing portion for the high pressure end, a casing portion for the low pressure end having a separating part projecting into said high pressure casing portion but spaced therefrom to form a high pressure fluid chamber, separate guide-means-carrying bodies supported and carried by said part projecting into said high pressure casing, and guide means supported and carried by said separate carrying bodies, a separate fluid chamber being formed between said separate carrying bodies and said separating part.
30. 6. In an elastic fluid turbine, the combination of a casing portion for the high pressure end, a casing portion for the low pressure end having a separating part projecting into said high pressure end casing portion toward the high pressure end, separate carriers supported and carried by the separating part, and guide means including diaphragms carried by said separate carriers, there being at least one fluid chamber between said separate carriers and said separating part.
7. In an elastic fluid turbine, the combination of a casing portion for the high pressure end, a casing portion for the low pressure end having a portion projecting therefrom into said high pressure casing portion towards the high pressure end thereof but spaced therefrom to form a fluid chamber around said projecting casing portion, separate carrying bodies carried and supported by the latter, and diaphragms provided with guide nozzle canals carried and supported by said separate carrying bodies, a separate fluid chamber being formed between said projecting casing portion and said separate carrying bodies.
8. In an elastic fluid turbine, the combination of a casing portion for the high pressure end, a casing portion for the low pressure end having a portion projecting therefrom into said high pressure casing portion towards the high pressure end thereof but spaced therefrom to form an outer high pressure fluid chamber around said projecting casing portion, separate carrying bodies carried and supported by the latter, and diaphragms provided with guide nozzle canals carried and supported by said separate carrying bodies, a separate inner fluid chamber being provided between said projecting casing portion and said separate carrying bodies, and said outer and inner fluid chambers being so located inside and outside of said projecting casing portion that one surrounds the other.
9. In an elastic fluid turbine, the combination of a casing portion for the high pressure end, a casing portion for the low pressure end having a portion projecting therefrom into said high pressure casing portion towards the high pressure end thereof but spaced therefrom to form a high pressure fluid chamber around said projecting casing portion, separate carrying bodies carried and supported by the latter, diaphragms provided with guide nozzle canals carried and supported by said separate carrying bodies, a separate fluid chamber being provided between said projecting casing portion and said separate carrying bodies, at least one of the fluid chambers being at the outside wall and at least another one at the inside wall of said projecting casing portion and said latter fluid chamber being surrounded by said outer fluid chamber.
10. In an elastic fluid turbine, the combination of a casing portion for the high pressure end, a casing portion for the low pressure end having a portion projecting

- therefrom into said high pressure casing portion towards the high pressure end thereof but spaced therefrom to form an outer fluid chamber around said projecting 5 casing portion, separate carrying bodies carried and supported by the latter, and diaphragms provided with guide nozzle canals carried and supported by said separate carrying bodies, a separate inner fluid chamber 10 being provided between said projecting casing portion and said separate carrying bodies, and the stationary diaphragms carried at the high pressure end of the first carrier body within said projecting casing 15 portion being surrounded by said outer fluid chamber.
11. In an elastic fluid turbine, the combination of a casing portion for the high pressure end, a casing portion for the low pressure end having a portion projecting therefrom into said high pressure casing portion towards the high pressure end thereof but spaced therefrom to form an outer fluid chamber around said projecting 20 casing portion, separate carrying bodies carried and supported by said projecting casing portion, and diaphragms provided with guide nozzle canals carried and supported by said separate carrying bodies, a separate 25 inner fluid chamber being provided between said projecting casing portion and said separate carrying bodies, the high pressure end of the highest pressure stationary guide means within said projecting casing portion 30 being surrounded by said outer fluid chamber and the high pressure end of following guide means being surrounded by said inner fluid chamber which is surrounded by said projecting casing portion and by said outer 35 fluid chamber.
12. In an elastic fluid turbine, the combination of a casing portion for the high pressure end, a casing portion for the low pressure end having a portion projecting 40 therefrom into said high pressure casing portion towards the high pressure end thereof but spaced therefrom forming an outer fluid chamber around said projecting portion and open at the high pressure end, and separate carrier bodies carried and supported by said projecting portion, at least 45 one inner fluid chamber being formed therebetween, and diaphragms provided with guide nozzle canals carried and supported by 50 said carrying bodies to form separate individual diaphragm groups, one surrounded at the high pressure end by said outer fluid chamber and another group by said separate inner fluid chamber which in turn is surrounded by the outer fluid chamber.
13. In an elastic fluid turbine, the combination of a casing portion for the high pressure end, a casing portion for the low pressure end having a carrying portion projecting therefrom into said high pressure 55 casing portion towards the high pressure end thereof but spaced therefrom to form a fluid chamber around said projecting portion open at the high pressure end, separate carrier bodies carried and supported by said projecting carrying portion, and diaphragms provided with guide nozzle canals carried and supported by said carrying bodies in separate individual diaphragm groups, one of said groups being surrounded at the high pressure end by said outer fluid chamber and the following group by at least another separate inner fluid chamber located within said projecting portion which is surrounded by the outer fluid chamber and a carrier body for such a diaphragm group being formed by one of the diaphragms of said group.
14. In an elastic fluid turbine, the combination of a casing portion for the high pressure end, a casing portion for the low pressure end having a carrying portion projecting therefrom into said high pressure casing portion towards the high pressure end thereof but spaced therefrom to form a fluid chamber around said projecting portion and open at the high pressure end, separate carrier bodies carried and supported by said projecting carrying portion, and diaphragms provided with guide nozzle canals carried and supported by said carrying bodies forming separate individual diaphragm groups, one of said groups being surrounded at the high pressure end by said outer fluid chamber and the following group by at least another separate inner fluid chamber located within said projecting portion which is surrounded by the outer fluid chamber and a carrier body for such a diaphragm group being formed by one of the diaphragms of said group and fluid-tight connected with the other diaphragms of the same group as well as carrying and supporting same independently of other groups.
15. In an elastic fluid turbine, the combination of a casing portion for the high pressure end, a casing portion for the low pressure end having a carrying portion projecting therefrom into said high pressure casing portion towards the high pressure end thereof but spaced therefrom to form a fluid chamber around said projecting portion open at the high pressure end, separate carrier bodies carried and supported by said projecting carrying portion, diaphragms provided with guide nozzle canals carried and supported by said carrying bodies and forming separate individual diaphragm groups, one of said groups being surrounded at the high pressure end by said outer fluid chamber and the following group by at least another separate inner fluid chamber located within said projecting portion surrounded by the outer fluid chamber and a carrier body for such a diaphragm group.

- being formed by one of the diaphragms of said group and fluid-tight connected with the other diaphragms of the same group carrying and supporting same independently of other groups, and said fluid chambers surrounding the higher pressure ends of said diaphragm groups and the carrier bodies thereof and being filled with fluid from the high pressure end of said groups.
16. In an elastic fluid turbine, the combination of an outer casing for the high pressure or admission end, a separate axially divided casing for the low pressure end having an axially divided casing portion projecting into said high pressure casing towards the high pressure end thereof, connecting means for said high pressure and low pressure casings, separate axially divided cylindrical carrier members supported and carried by said projecting casing portion by means of a male and female connection therebetween for each carrier member, said latter connections providing a radial clearance, and diaphragms carried and supported by said carrier members and connected fluid-tight therewith.
17. In an elastic fluid high pressure turbine, the combination of a casing for the high pressure side, a casing for the low pressure side, connecting or coupling means connecting said casings, a diaphragm carrying portion connected with said casing for the lower pressure side, and spaced from the high pressure casing to form a high pressure fluid chamber therebetween a separate carrier body provided within said carrying portion and carried thereon by means of radial abutting surfaces forming a fluid-tight connection and a radial clearance, and diaphragms carried by said carrier body and connected fluid-tight therewith.
18. In an elastic fluid high pressure turbine, the combination of a casing for the high pressure side of a material of high tensile strength a casing for the low pressure side made of a suitable cast metal, a threaded connection around said casings, a carrying portion on said low pressure end casing, a separate carrier body therein carried and supported by said carrying portion by means of abutting side surfaces, radial clearances being formed between the axial surfaces, and diaphragms with nozzles fluid-tight connected with said carrier body.
19. In an elastic fluid high pressure turbine, the combination of a casing for the high pressure side of a material of high tensile strength, a casing for the low pressure side made of suitable cast metal, a connecting and retaining sleeve surrounding said casings for coupling them together, a carrying portion on said low pressure end casing, a separate carrier body therein carried and supported by said carrying portion by means of abutting side surfaces and forming radial clearances between the axial surfaces, and diaphragms with nozzles having fluid-tight connections with said carrier body by means of abutting side surfaces.
20. In an elastic fluid turbine, the combination of a rotor, sealing means and bearings for said rotor, said rotor having rotor wheels and moving blades thereon, stationary diaphragms and guide canals between said rotor wheels, separate rotor enclosing carrier bodies for said diaphragms forming separate diaphragm groups within said turbine, at least one fluid jacket surrounding said rotor enclosing carrier bodies, an outer carrier for said rotor enclosing carrier bodies outside thereof forming an inner casing portion, and an outer casing portion outside thereof suitably connected with said inner casing portion, a fluid chamber being formed between said outer and inner casing portions surrounding said inner casing portion on the outside thereof and surrounded by the other fluid chamber.
21. In a high pressure elastic fluid turbine the combination of an outer high pressure casing, an inner casing concentric with the outer casing and spaced therefrom to form a high pressure chamber therebetween, separate diaphragm carrier bodies carried within and supported by said inner casing, said bodies being spaced from the inner casing to form a steam chamber therebetween and being supported by said inner casing by means of a ring groove and a radially adjustable connection.
22. In a high pressure elastic fluid turbine, the combination of an outer casing, an inner casing disposed concentrically within and spaced from the outer casing to form a high pressure fluid chamber therebetween, a separate diaphragm carrier body disposed within and carried by said inner casing, said diaphragm carrier being spaced from the inner casing to form a steam chamber therebetween and being supported therefrom by means of a groove and cylindrical projecting connection which is fluid-tight and permits radial relative movements between the two parts.
23. A turbine of the characters set forth in claim 22 wherein the diaphragm carrier body is normally held in position by the abutting side surfaces of the groove and cylindrical projecting connection.
24. A high pressure elastic fluid turbine comprising an outer high pressure casing of high tensile strength enclosing the high pressure end of the turbine and a casing for the low pressure end of the turbine having a shoulder disposed within and engaged by the low pressure end of the high pressure casing, a cylindrical rotor-enclosing part projecting from the low pressure casing towards the high pressure end of the turbine and spaced from the outer casing to

form a high pressure steam chamber there-between, supporting diaphragm carrier bodies disposed within the rotor-enclosing casing and supported therefrom by means of 5 radially adjustable connections and a steam chamber being formed between said carrier bodies and the rotor-enclosing casing.

25. In a high pressure elastic fluid turbine the combination of an outer casing, an inner 10 casing disposed concentrically within and spaced from the outer casing to form a high pressure fluid chamber therebetween, a separate high pressure diaphragm carrier body disposed within and carried by said inner casing, said diaphragm carrier being spaced 15 from the inner casing to form a steam chamber therebetween and being supported therefrom by means of a fluid tight connection

permitting radial relative movements between the parts, and diaphragms carried by 20 said separate carrier body.

26. In a high pressure elastic fluid turbine the combination of an outer casing, an inner 25 casing disposed concentrically within and spaced from the outer casing to form a high pressure fluid chamber therebetween, a separate diaphragm carrier body disposed within and carried by said inner casing, said carrier body being supported from the inner casing by means of a fluid tight connection permitting 30 radial relative movements between the two parts, and diaphragms carried by said separate carrier body.

In testimony whereof I affix my signature.

FRANZ LÖSEL.
